(57) **CLAIM**

The ornamental design for a charger for an electronic cigarette, as shown and described.

DESCRIPTION

FIG. 1 is a front view of a charger for an electronic cigarette according to the present application;
FIG. 2 is a rear view of the charger for the electronic cigarette according to the present application;
FIG. 3 is a left view of the charger for the electronic cigarette according to the present application;
FIG. 4 is a right view of the charger for the electronic cigarette according to the present application;
FIG. 5 is a top view of the charger for the electronic cigarette according to the present application;
FIG. 6 is a bottom view of the charger for the electronic cigarette according to the present application;
FIG. 7 is a first perspective view of the charger for the electronic cigarette according to the present application;
FIG. 8 is a second perspective view of the charger for the electronic cigarette according to the present application; and,
FIG. 9 is an enlarged bottom view of the charger for the electronic cigarette according to the present application.
The broken lines in the drawings illustrating environmental structure or boundaries form no part of the claimed design.

1 Claim, 9 Drawing Sheets
